US0D1040179S

(12) **United States Design Patent** (10) Patent No.: **US D1,040,179 S**
(45) Date of Patent: ** Aug. 27, 2024

(54) **DISPLAY SCREEN OR PORTION THEREOF WITH GRAPHICAL USER INTERFACE**

(71) Applicant: **Beckman Coulter, Inc.**, Brea, CA (US)

(72) Inventors: **Brittany R. Baker**, Arlington, MN (US); **Daniel Sunoh Choe**, Minneapolis, MN (US); **Andrew Cottrell**, Minneapolis, MN (US); **Dana Vajen Habig**, Cincinnati, OH (US); **Tony J. Riley**, Minneapolis, MN (US); **Mindie Seh-wha Te**, Fullerton, CA (US); **XiaoYin Wang**, Suzhou (CN); **Chad M. Weber**, Shakopee, MN (US)

(73) Assignee: **BECKMAN COULTER, INC.**, Brea, CA (US)

(**) Term: **15 Years**

(21) Appl. No.: **29/852,301**

(22) Filed: **Sep. 6, 2022**

(57) **CLAIM**

The ornamental design for a display screen or portion thereof with graphical user interface, as shown and described.

DESCRIPTION

The FIGURE is a front view of a display screen or portion thereof with graphical user interface.

The outermost dot-dash broken lines in the figure illustrate a display screen or portion thereof that forms no part of the claimed design. The remaining dashed broken lines in the figure illustrate portions of the graphical user interface that form no part of the claimed design.
